UNITED STATES PATENT OFFICE

JAMES KERR, OF WILLIAMSPORT, PENNSYLVANIA, ASSIGNOR TO WILLIAMSPORT
FURNITURE COMPANY, A CORPORATION OF PENNSYLVANIA

DESIGN FOR A CONSOLE VANITY TABLE

Application filed January 29, 1931. Serial No. 38,478. Term of patent 3½ years.

To all whom it may concern:

Be it known that I, JAMES KERR, a citizen of the United States of America, residing at Williamsport, in the county of Lycoming and State of Pennsylvania, have invented a new, original, and ornamental Design for Console Vanity Table, of which the following is a specification, reference being had to the accompanying drawing, forming part thereof.

The figure is a view in perspective of a console vanity table, showing my new design.

I claim:

The ornamental design for a console vanity table, as shown.

JAMES KERR.
